UNITED STATES PATENT OFFICE.

JAMES N. HEALD, ALBERT TURNER, AND GEORGE C. KIMMEL, OF WORCESTER,
MASSACHUSETTS, ASSIGNORS TO THE HEALD MACHINE COMPANY, OF WORCESTER,
MASSACHUSETTS, A CORPORATION OF MASSACHUSETTS.

GRINDING MACHINE.

Application filed October 7, 1922. Serial No. 583,113.

To all whom it may concern:

Be it known that we, JAMES N. HEALD, ALBERT TURNER, and GEORGE C. KIMMEL, all citizens of the United States, residing at Worcester, in the county of Worcester and Commonwealth of Massachusetts, have invented a new and useful Improvement in a Grinding Machine, of which the following, together with the accompanying drawings, is a specification.

The present invention relates to grinding machines, and particularly to improvements in the construction and operation of the wheel feeding instrumentalities of a machine for grinding exterior cylindrical surfaces, although, obviously, not limited to a machine of such type.

The several features of the invention are described hereinafter and specifically pointed out in the appended claims, reference being had to the accompanying drawings, wherein—

Fig. 1 is a view in front elevation of a grinding machine embodying the invention.

Fig. 2 is a similar view, on a larger scale, showing the wheel feeding mechanism removed from the front of the machine.

Fig. 3 is a top plan view of said mechanism.

Fig. 4 is a transverse sectional view of said mechanism.

Figs. 5 and 6 are respectively plan and sectional views of a mechanism for varying the stroke of a feeding pawl.

Figs. 7, 8 and 9 are large scale views, illustrating the operation of stopping mechanism, operable in connection with the feed of the grinding wheel by hand, and showing the parts in three different positions.

Figs. 10 and 11 are respectively front and sectional views on an enlarged scale, of an adjusting device carried by the hand wheel of the machine.

Figs. 12 and 13 are respectively front and sectional views of certain adjustable stops adapted to be used with said hand wheel.

Fig. 14 is a plan view, partly in section, of a feed actuating mechanism adapted to operate independently of the travel of the table.

Figs. 15 and 16 are front views of said feed actuating mechanism, showing it respectively in operative and inoperative position.

Like reference characters refer to like parts in the different figures. 55

The invention is shown in connection with a grinding machine for operation on exterior cylindrical surfaces, having a base 1 which provides longitudinal ways 2 for the reciprocatory movement of a work carrying table 3; the work to be ground is supported in the well known manner between centers 4 and 5 provided, respectively, by a head stock 6 and a tail stock 7, both carried by table 3 and adjustable thereon to accommodate pieces of work of different lengths. The head stock 6 provides the usual means, not shown, for engaging the work, and rotating it on the axis provided by the centers 4 and 5; this rotation, in conjunction with the simultaneous reciprocation of the work afforded by movement of table 3, subjects all portions of its surface to the action of a rotating grinding wheel 8, which is suitably journaled in a head or slide 9, the latter, by its movement in suitable transverse ways 9', Fig. 4, procuring the feed of the grinding wheel toward and from the work axis. 75

The movement of table 3, to carry the rotating work back and forth in contact with the grinding wheel 8, may be effected by any desired means, such as a fluid pressure controlling and reversing mechanism of the type, for instance, disclosed in the copending applications of Drake & Hubbell, Serial No. 528,118, filed January 9, 1922, and Heald & Turner, Serial No. 574,940, filed July 14, 1922. The construction and operation of this mechanism for reciprocating the work forms no part of the present invention it being sufficient to note that a reversing valve for the motive fluid, not shown, is operable by a lever 10, the latter having a pin and slot connection, likewise not shown, with a rocking member 11, whose upper end projects into the path of a pair of adjustable dogs 12 and 13 carried by the table 3. These stops or dogs 12 and 13 engage the member 11 alternately whereby to reverse the direction of travel of the table 3 at each engagement; their longitudinal adjustment determines the throw, or length of table travel, for any given operation. 100

The cross-feed movement of wheel head

9 is obtained by the usual main screw shaft 14, Fig. 4, which cooperates with a nut 14', attached to the wheel head, to cause movement of the latter toward and from the work. In one of its aspects, the invention contemplates the feed of the grinding wheel toward the work in response to the reciprocations of the table 3, the stops or dogs 12 and 13 being utilized for successive actuations of the wheel feeding mechanism to procure a predetermined feed of the grinding wheel after each traversing movement of the work.

To this end a member 15, pivoted to the machine frame at 16, carries a roller 17 which is disposed in the path of projections 18 and 19 provided respectively by the dogs 12 and 13. A link 20 connects member 15 to a rocker arm 21, the latter adapted to swing on the axis provided by a shaft 22, on which is also journalled a ratchet wheel 23. A spring 24, attached to arm 21, acts yieldingly to draw said arm about its axis in a clockwise direction, Fig. 2, and thus holds the roller 17 of member 15 in position to be engaged by the travelling projections 18 and 19. These projections, at each engagement with roller 17, act to depress the free end of member 15 and thus, through link 20, to rotate the arm 21 counterclockwise through a small arc; a pawl 25, carried by said arm, operatively engages the teeth of ratchet wheel 23, and thus effects a counterclockwise rotation of said ratchet wheel through the same arc. On the return movement of arm 21, under the influence of spring 24, the pawl 25 simply slides back inoperatively over the ratchet teeth. The hub of ratchet wheel 23 is extended inwardly to provide a pinion 26 which meshes with a gear 27 on main screw shaft 14; in this way, each angular displacement of ratchet wheel 23 is communicated to the feed-screw, to effect a lateral shifting of the wheel head 9; the feed-screw however has only a very small angular movement, in comparison to the angular movement of ratchet wheel 23, because of the gearing 26, 27—the arrangement being such as to require, for instance, five complete revolutions of the ratchet wheel for one revolution of the feed-screw.

At each engagement of the roller 17 with the traveling projections 18 and 19, the member 15 is always depressed to the same level, due to the fact that no further downward movement of the roller 17 can be produced by further movement in either direction of the table 3, after said roller reaches the horizontal alined surfaces 18' and 19' of said projections. In this way, the operative stroke of arm 21 is made to terminate always at the same point, and thus the feed of ratchet wheel 23 by pawl 25 is not subject to any such accidental variation as would be apt to result from the table 3 travelling at a

high speed, or from the tendency of said table, by reason of its inertia, to drift beyond the point selected for its reversal. In other words, regardless of variations in the movements of the table, the movements of the roller 17 produced by said table never exceed a predetermined amount, and the excess movements of the table are without effect on said roller.

In conjunction with the above described means for insuring the stoppage of pawl 25 always at the same point on its operative stroke, the invention provides means for adjusting the travel of said pawl on its return or inoperative stroke, whereby the operator is enabled to fix with exactitude the number of ratchet teeth on wheel 23 that will be picked up by the pawl, for any given feeding operation. To this end, the return or clockwise movement of arm 21, under the influence of spring 24, is subject to limitation by means of an irregular rotatable cam 28 disposed in the path of a projection 29 of link 20, Fig. 5. The cam 28 is journalled on a stationary stud 30, as shown in Fig. 6, and is provided with suitable means for turning it by hand such as a knob 31. A spring pressed pin 32, cooperating with suitable shallow depressions 33 in the bottom of cam 28, insures the correct disposal of said cam in the various positions of adjustment to which it may be turned, for the purpose of opposing its high, low, or intermediate portions, as desired, in the path of projection 29. The handle 31 is preferably so inscribed as to indicate the adjustment of the cam 28, with reference to an index mark on the stud 30, as shown in Fig. 5,—thus enabling the operator to fix in advance the number of ratchet teeth on wheel 23 to be picked up by pawl 25 at each stroke of arm 21, to give a fine, medium or coarse feed of the grinding wheel, as desired.

The feeding mechanism provides the usual hand wheel 34, which is also loosely journalled on shaft 22, the same as the ratchet wheel 23. Said hand wheel 34 has secured thereto a radially disposed bracket 35, Figs. 10 and 11, which provides a journal portion 36 for the reception of a rotatable member 37, the latter adapted to be turned by a knob 38, Fig. 10. The connection of knob 38 to member 37, for turning the latter, is by means of a spindle 39, secured to said handle and keyed to said member; the spindle 39 provides a normally projecting toothed portion 40, adapted to mesh with the teeth of ratchet wheel 23. A spring pressed pin 41, adapted to enter a series of notches 42 provided by member 37, operates as a friction lock to prevent accidental displacement of member 37 and spindle 39 and thus serves to insure rotation in unison of hand wheel 34 and ratchet wheel 23, except when the handle 38 is seized and turned on its own

- axis, or when said handle is pulled back to 50 retract the pinion teeth 40 from their engagement with the teeth of wheel 23; this last named retraction is accomplished by 55 the compression of a spring 43, which normally holds the pinion teeth and ratchet teeth in engagement, as shown in Fig. 11, to lock the hand wheel and ratchet wheel together.
- 10 The hand wheel 34 carries on its periphery an inwardly projecting plate or shield 44, Figs. 2 and 10; this shield 44 is preferably, though not necessarily, carried by the bracket 35 of said hand wheel and, being disposed in overlying relation to the ratchet teeth of wheel 23 is adapted, when carried into the zone of action of pawl 25, to prevent operative engagement of said pawl with said ratchet teeth. In other 20 words, the shield 44 may be set or fixed to intercept the pawl, following a predetermined automatic feed of the grinding wheel by said pawl, whereby to discontinue said feed as soon as the work has been ground 25 down to a predetermined diameter.
- With the ratchet wheel 23 in the exact position that it assumes for a given desired diameter, the hand wheel 34 is adjusted, relative to the ratchet wheel 23, to bring the 30 shield 44 into position for just intercepting pawl 25; this is done by retracting knob 38 so as to allow free movement of the hand wheel without disturbing the exact setting of the ratchet wheel. Thereupon, the knob 38 is released, allowing the hand wheel and 35 ratchet wheel to be locked together again by the meshing of pinion teeth 40 with the teeth of the ratchet wheel. With the shield 44 thus adjusted in fixed relation to 40 a predetermined tooth on the ratchet wheel 23, the grinding wheel 8 can be fed backward to allow the introduction of an unground piece of work; with this setting of the shield 44 maintained, subsequent automatic feeding of the grinding wheel by the 45 action of pawl 25 is always interrupted at the proper time, to prevent the work from being ground below the predetermined desired diameter. It is to be noted in this 50 connection that the step-by-step rotation of knob 38, past the successive notches 42, provides for a delicate adjustment of the shield 44 in bringing it exactly to its desired pawl-intercepting position. This delicate adjustment is useful not alone in obtaining 55 the exact setting of shield 44, but can also be availed of to readjust said shield from time to time, to compensate for the gradual wearing down of the surface of grinding 60 wheel 8.
- In another of its aspects, the present invention contemplates improved means for feeding to exact predetermined size, when the feed of the grinding wheel is obtained 65 by hand,—that is, by rotation of the hand wheel 34, to obtain a straight grinding cut on work that does not require any traversing movement across the periphery of the grinding wheel. In the operation of feeding the grinding wheel by hand, as above described, 70 the attainment of the desired diameter for an initial piece of work leaves the ratchet wheel 23 in the exact position necessary for it to assume for all subsequent reproductions of the same desired diameter; and before the grinding wheel is fed backward from this position to permit the insertion of a new piece of work between the centers 4 and 5, an adjustable stopping means may be fixed in position to prevent the movement of the ratchet wheel 23 beyond this self-same position, in the subsequent hand-fed operations of the machine, to produce pieces of the same diameter.
- 75 Said stopping means comprises a projection 45 carried by hand wheel 34, and preferably, though not necessarily, extending from the bracket 35 of said hand wheel,—said projection 45 cooperating with a stop which is here shown as constituted by the 80 end of a lever 46, adapted to be interposed in the path of said projection. The procedure is as follows:—Without disturbing the above described final position of ratchet wheel 23, the hand wheel 34 is turned to carry the projection 45 into exact engagement 85 with the end of lever 46; this may be done by revolving knob 38 to click or rack the hand lever 34 through the necessary distance, but is preferably done much more 90 quickly by retracting the knob 38 and then turning the hand wheel freely counterclockwise until the projection 45 and stop 46 come together, following which the return of knob 38 to its normal position again 95 locks the hand wheel and the ratchet wheel together for movement in unison. Thereupon, the grinding wheel is fed backward, by clockwise rotation of the hand wheel, 100 to permit the insertion of a new unground piece of work, and it is obvious that, unless it has been necessary, for this purpose, to run back the hand wheel through more than one revolution, the new piece of work, 105 and other subsequent pieces, will be brought to exact size when the projection 45 again 110 engages the interposed stop 46, to prevent further counterclockwise rotation of the hand wheel.
- 115 However, it frequently happens that the operator must run the hand wheel 34 back through more than one revolution in order to insert the new piece of work between the centers 4 and 5; under these conditions, the stop lever 46, if maintained in the path of projection 45, would bring about the stoppage 120 of the hand feed too soon,—that is, with the hand wheel still having one or more revolutions to make before the work would be 125 ground to the desired size. The present in- 130

vention contemplates an automatic control of the stop lever 46 to take care of this contingency; to this end, said lever is pivoted for movement about an axis provided by a stud 47, and has secured thereto an arm 48, whose end rides in contact with an irregular cam 49. The cam 49 is carried by an outward extension of the main feed screw 14, being normally rotatable with said feed screw, at a speed much reduced from that of the ratchet wheel and hand wheel, by the friction of a coil spring 50 bearing against the inner face of said cam; this frictional connection between the cam 49 and the feed screw 14 allows the operator, by means of a disk or knob 51 secured to the cam, to shift the cam by hand into any desired angular position on the shaft 14, which position will be maintained during the rotation of said shaft, by spring 50, until the operator again sees fit to change it.

The cam 49 presents for successive contact with arm 48, an extended concentric portion 52, a lower portion 53 and a high point 54. When the above described setting of projection 45 is made, for the purpose of stopping further inward feed upon the ratchet wheel's travel to a predetermined position, the cam 49, at the same time, is turned on screw shaft 14 into the position shown in Fig. 7, where the lower portion 53 opposes the arm 48, and where a spring pressed pin 55 carried by arm 48, bottoms in a stationary notch 56, whereby to retain the end of lever 46 in the path of projection 45. Following this setting, the grinding wheel is fed backward in the usual way by the movement of hand wheel 34 and ratchet wheel 23 in unison; such movement causes counterclockwise rotation of cam 49, to bring the concentric portion 52 of said cam against the arm 48, and it is particularly to be noted that the gear reduction above described, between the parts, is such that several complete revolutions of the hand wheel can be made without disturbing this relation, i. e., the travel of arm 48 on concentric portion 52, as shown in Fig. 8.

In this position of the parts, the end of stop lever 46 is held just out of the path of projection 45, as shown in Fig. 8, with the spring pressed pin 55 partially withdrawn from the stationary notch 56. Thus, on the return or inward feed of the grinding wheel, by the counterclockwise rotation of hand wheel 34, the cam 49 holds the stop 46 in inoperative position through the same desired number of revolutions of the hand wheel; on the last revolution of this inward hand feed, the low portion 53 of the cam comes opposite the arm 48, and the pin 55, by bottoming in notch 56, throws the end of stop lever 46 into operative position in the path of projection 45. It is to be noted in this connection that the low portion 53 of

cam 49 is extended to embrace a considerable arc; this permits the above described action to take place notwithstanding such further fine adjustments as are made from time to time by rotation of knob 38, to compensate for the gradual wear of the grinding wheel.

From the foregoing, it will be clear that the hand feed stopping mechanism is so constructed as to automatically and properly control the position of stop 46 in feeding operations that require several complete revolutions of the hand wheel,—in this case, for instance say five revolutions, as determined by the five-to-one gear reduction between the hand wheel and the main feed screw 14. In such cases as require more than five backward turns of the hand wheel, i. e., one complete revolution of cam 49, the high point 54 of said cam strikes the arm 48 and throws the pin 55 out of notch 56 and into an adjacent notch 57, as shown in Fig. 9, thus rendering the stop 46 wholly inoperative, and requiring its return by the operator to normal position after the inward feed of the grinding wheel has progressed far enough to bring cam portion 52 opposite the arm 48.

In still another of its aspects, the invention involves mechanical means for procuring the feed of the grinding wheel on straight in-cuts, i. e., when there is no traversing of the wheel by the work and hence no engagement of member 15 to actuate pawl 25. Under these conditions, the drive for the feed is from a suitably journaled rotating shaft 58, Figs. 3, 14, 15 and 16, said shaft being driven in any suitable manner as by means of a sprocket wheel 59 thereon which may be connected by a sprocket chain, not shown, with a suitable driving sprocket on the main shaft of the machine, not shown. On one end said shaft 58 carries an eccentric pin 60, the latter projecting into the hole or opening 61 of a member 62, and carrying a contact roll 63. The member 62 is pivoted at 64 to the arm 21, and in one position of said member, as illustrated in Fig. 16, a spring pressed pin 65, engageable in a notch provided by extension 66 of arm 21, maintains said member 62 under the influence of the rotating eccentric contact roll 63, whereby to produce the oscillation of lever 21 and the consequent automatic feed of the grinding wheel, through pawl 25 and ratchet wheel 23. It will be understood that the limiting mechanism shown in Figs. 5 and 6, heretofore described in connection with the table feed of the grinding wheel, is also operable, under these conditions, to produce a fine, coarse, or medium feed of the grinding wheel. When the table feed is operative, or when it is desired to feed by hand instead of mechanically, the pin 65 is retracted, and the member 62 is swung upwardly on its

- 5 pivot 64 into the position shown in Fig. 14, where the pin 65, entering another notch in extension 66, retains said member 62 out of contact with the rotating eccentrically disposed contact roll 63. In connection with this type of mechanical feed, which is useful more especially in grinding short pieces that do not require traverse of the wheel, the cessation of feed, when the work is 10 ground to size, is accomplished for each piece by a proper setting before hand of shield 44, in precisely the same manner as described for the table-feed mechanism, to throw out the pawl 25.
- 15 In the production of shouldered work, where the grinding wheel is fed in by hand, to bring to size successively, portions of larger and smaller diameters on the same piece of work, it is of advantage to use, in connection with the stop 46, a plurality of cooperating devices 67, 67, adjustable on the periphery of hand wheel 34, as shown in Figs. 12 and 13. Each device 67 is made in two parts and said parts are adapted to be 20 drawn together by a screw 68, which serves to retain the device in the desired position of adjustment on the periphery of the hand wheel. Each device 67 provides a projection 25 69, for engagement with the stop 46, and the several devices are so spaced apart on the hand wheel as to procure successive stoppages of the hand feeding as each diameter, from the largest to the smallest is reached,—it being understood, of course, that following stoppage of the feed in each case, the work is shifted longitudinally and the stop lever 46 is rocked by hand to allow a projection 69 to pass, and then returned to operative position into the path of the next 30 projection 69. Where the difference in diameter is very small, provision is made for a close setting of the adjacent devices 67, 67, by using one of them with an oblique side, as shown at 70, Fig. 12.
- 45 We claim:
1. In a grinding machine, wheel feeding mechanism comprising a ratchet-wheel operatively connected to the main feed screw, a hand wheel concentric with said ratchet-wheel and a rotatable pinion carried peripherally by said hand wheel and movable into and out of mesh with the teeth of said ratchet-wheel, in combination with a cylindrical member of larger diameter than said pinion and rotatable therewith, said member having a series of spaced peripheral depressions, and a spring-pressed pin adapted to enter said depressions to restrain rotation of said pinion, whereby to form a substantially positive lock between said hand wheel and said ratchet-wheel except when said pinion is seized and axially turned to overcome the friction of said pin, in the act of adjusting the hand wheel relative to the ratchet-wheel.
  2. In a wheel feeding mechanism for grinding machines, a main feed screw, a hand wheel, means for normally operatively connecting said hand wheel and said main feed screw, a stop, and a projection carried by the hand wheel, the latter being movable, when desired, independently of the main feed screw to procure engagement of said projection and said stop in a predetermined work-sizing position of the grinding wheel, in combination with a cam operable on said stop, and rotatable, at a reduced speed, from said hand wheel, said cam providing a relatively short portion corresponding to the operative disposal of said stop in the path of said projection, and an extended concentric portion adapted to maintain said stop out of the path of said projection until said hand-wheel's final revolution, in bringing the grinding wheel to said predetermined position, is reached.
  3. In a wheel feeding mechanism for grinding machines, a main feed screw, a hand wheel, means for normally operatively connecting said hand wheel and said main feed screw, a stop, and a projection carried by the hand wheel, the latter being movable, when desired, independently of the main feed screw to procure engagement of said projection and said stop in a predetermined work-sizing position of the grinding wheel, in combination with a cam operable on said stop, and rotatable, at a reduced speed, from said hand wheel, said cam providing a relatively short portion corresponding to the operative disposal of said stop in the path of said projection, and an extended concentric portion adapted to maintain said stop out of the path of said projection until said hand-wheel's final revolution, in bringing the grinding wheel to said predetermined position, is reached.
  4. In a wheel feeding mechanism for grinding machines, a main feed screw, a hand wheel, means for normally operatively connecting said hand wheel and said main feed screw, a stop, and a projection carried by the hand wheel, the latter being movable, when desired, independently of the main feed screw to procure engagement of said projection and said stop in a predetermined work-sizing position of the grinding wheel, in combination with means operable during subsequent inward and outward operative feeding revolutions of the hand wheel for maintaining said stop out of the path of said projection until said hand-wheel's final revolution, in bringing the grinding wheel to said predetermined position, is reached.

said means comprising a cam frictionally driven from the main feed screw, and shiftable angularly thereon.

5. In a wheel feeding mechanism for grinding machines, a main feed screw, a hand wheel, means for normally operatively connecting said hand wheel and said main feed screw, a stop, and a projection carried by the hand wheel, the latter being movable, 10 when desired, independently of the main feed screw to procure engagement of said projection and said stop in a predetermined work-sizing position of the grinding wheel, in combination with means operable during 15 subsequent inward and outward operative feeding revolutions of the hand wheel for maintaining said stop out of the path of said projection until said hand-wheel's final revolution, in bringing the grinding wheel 20 to said predetermined position, is reached, said means comprising a cam frictionally driven from the main feed screw, and shiftable angularly thereon, said cam having a depressed portion corresponding to the 25 operative disposal of said stop in the path of said projection, and said depressed portion being extended to permit fine adjustments of predetermined work-sizing position 30 of the grinding wheel, to compensate for wear of the latter.

6. In a wheel feeding mechanism for grinding machines, a main feed screw, a hand wheel, means for normally operatively

connecting said hand wheel and said main feed screw, a stop, and a projection carried by the hand wheel, the latter being movable, when desired, independently of the main feed screw to procure engagement of said projection and said stop in a predetermined work-sizing position of the grinding wheel, in combination with a cam operable on said stop, and rotatable, at a reduced speed, from said hand wheel, said cam providing a relatively short portion corresponding to the operative disposal of 45 said stop in the path of said projection, and an extended concentric portion adapted to maintain said stop out of the path of said projection until said hand-wheel's final revolution, in bringing the grinding wheel to 50 said predetermined position is reached, and said cam further providing a projection adapted to render said stop inoperative when the hand wheel, in backward feeding, is turned through more revolutions than 55 the number corresponding to a single revolution of said cam, and a spring pressed pin carried by said stop, for cooperation with a pair of notches, to retain said stop in the 60 respective positions to which it is moved by said cam.

Dated this third day of October, 1922.

JAMES N. HEALD.
